PERCUSSION FUSE FOR BOMBS AND
SIMILAR PROJECTILESLuigi Savani, Milan, Italy, assignor to Societa
Italiana Ernesto Breda per Costruzioni Mec-
caniche, Milan, ItalyApplication July 13, 1934, Serial No. 735,034
In Italy July 14, 1933

13 Claims. (Cl. 102—39)

This invention relates to improvements in or modification of the invention claimed in Letters Patent No. 1,826,190.

The above-mentioned patent relates to a percussion fuse for bombs and similar projectiles in which two heavy semispherical masses, preferably formed of an obnoxious or explosive material, press, at the moment of impact, against plates which are opposite one another and which carry respectively the striker and the percussion cap and are held spaced apart by a spring and a safety device. This safety device comprises a slide slidably mounted between the two discs and hinged at one end to a cowl covering the dome 10 of the bomb. The other end of the cowl is detachably connected to the dome of the bomb by means of a pin which can be disengaged and removed by hand shortly before throwing the bomb.

20 This device operates effectively in the case of bombs which are thrown by hand. When, however, the fuse is to be applied to projectiles which are adapted to be thrown by explosion, various disadvantages may arise. In fact the projectile still has to be handled for some time after the safety device has been removed and this may lead to an explosion. The invention has for its subject modifications in the safety device which, while enabling the hand to be removed if necessary, permits its release to be effected automatically at the moment of throwing by explosion.

25 The fuse according to the present invention is provided with an annular heavy mass which embraces the body of the fuse. Normally, the annular mass is held in a position to retain the safety device in its safety position and is adapted to be shifted to release the safety device due to the action of inertia when the bomb is projected. The annular mass may be provided with a projection which normally engages a pin connected to the cowl or with a pin engaging an eye on the cowl. In either case the mass is shifted by inertia to a disengaging position.

30 The accompanying drawings show by way of example and not in a limiting sense, three different forms of construction.

35 Figure 1 is an axial sectional view of a device according to the present invention with the safety device in safety position.

40 Fig. 2 is a view similar to Fig. 1 with the safety device in disengaged position.

45 Fig. 3 is a cross-sectional view taken on line A—B of Fig. 1.

50 Figs. 4 and 5 are views corresponding to Figs.

1 and 2, illustrating a modified form of my invention.

5 Figs. 6 and 7 are views corresponding to Figs. 1 and 2, illustrating a further modified form of my invention.

In each of the forms of construction shown there are provided, as in the above mentioned patent, two discs 1, 2, which respectively carry the firing pin 3 and the detonator cap 4, which are spaced apart by the spring 5 and which can 10 be pushed one against the other by the semispherical masses 6, 7. A slide 8 is interposed between the two discs 1, 2 and prevents the approach until the cowl 9, which is hinged to the said slide at 10, is disengaged from a suitable 15 catch which is suitably located on the edge of the cowl diametrically opposite to the hinge 10, which cowl flies off under the action of the wind.

Also in each of the forms of construction shown there is provided an annular mass 11 which is 20 held by frangible members 2' in a position advanced towards the safety slide and which is provided with suitable means for holding the said safety device in position. At the moment of throwing by explosion, the said annular mass 25 recoils under the action of inertia from the position shown in Figs. 1, 4 and 6 to that shown in Figs. 2, 5 and 7, the members 2' being easily broken or deformed by the action of inertia on the annular mass. The safety device is thus 30 free, so that the cowl 9 opens as the projectile is moved through the air and removes the spacing slide 8 thus placing the projectile into a condition for exploding.

35 In the form of construction shown in Figs. 1 to 3 the locking member is formed by a pin 12 corresponding to the pin, which is releasable and removable by hand, in the aforementioned patent. The projection 13 of the annular mass 11 prevents the pin 12 from passing out of the slot 40 14 provided in the body 15 of the bomb as long as the said mass has not recoiled. After recoil the pin is disengaged from the fuse remaining attached to the cowl 9. This opens and drops off with the slide. This arrangement enables 45 the projectile provided with this fuse to be used for throwing by hand or by explosion. When, however, the projectile is only to be thrown by explosion, the construction of the fuse may be simplified by omitting the pin 12 and engaging 50 a pin 16, secured to the annular mass 11, with an eye 17 secured to the cowl 9 as shown in Figs. 4 and 5. This cowl may also be provided with a wing 18, hinged at 19, as shown in Figs. 6 and 7 for the purpose of facilitating the disengagement 55

when the fuse is applied to projectiles thrown by rifled arms in such a manner that they also receive a rotary movement. In these cases centrifugal force commences the disengagement of the cowl by opening the wing 18. It will, however, be understood that other known devices may be used for ensuring that the explosion of the projectile can only take place at a sufficient distance from the throwing arm.

10. What I claim is:

1. In a projectile fuse, the combination comprising a detonator cap and a firing pin mounted for relative movement longitudinally of the fuse, safety means removably mounted in said fuse for preventing contact between the firing pin and detonator cap, means on the fuse removable by impingement of the air through which the projectile moves in flight for retaining and removing the safety means, and inertia responsive means for locking the air impinged means against removal.

2. In a projectile fuse, the combination comprising a detonator cap and a firing pin mounted for relative movement longitudinally of the fuse, safety means removably mounted in said fuse for preventing contact between the firing pin and detonator cap, means on the fuse removable by impingement of the air through which the projectile moves in flight for retaining and removing the safety means, inertia responsive means for locking the air impinged means against removal, and frangible means adapted to break under the impact of projection for retaining the inertia responsive means in locking position.

3. In a projectile fuse, the combination comprising a detonator cap and a firing pin mounted for relative movement longitudinally of the fuse, safety means removably mounted in said fuse for preventing contact between the firing pin and detonator cap, air impinged means connected to the safety means for retaining the same in and removing it from the fuse, an inertia responsive body positioned in said fuse for movement longitudinally thereof, a manually removable safety pin extending through said air impinged means, a lug on said body adapted when the body is in its forward position to engage said safety pin to retain the air impinged means and safety means in assembled relation, and means normally retaining said body in a forward position.

4. In a projectile fuse, the combination comprising a detonator cap and a firing pin mounted for relative movement longitudinally of the fuse, safety means removably mounted in said fuse for preventing contact between the firing pin and detonator cap, air impinged means connected to the safety means for retaining the same in and removing it from the fuse, an inertia responsive body positioned in said fuse for movement longitudinally thereof, a manually removable safety pin extending through said air impinged means, a lug on said body adapted when the body is in its forward position to engage said safety pin to retain the air impinged means and safety means in assembled relation, and frangible means normally retaining said body in a forward position and adapted to break under projection impact to permit said body to move relatively to the fuse to move the lug out of engagement with the safety pin.

5. In a projectile fuse, the combination comprising a detonator cap and a firing pin mounted for relative movement longitudinally of the fuse, safety means removably mounted in said fuse

for preventing contact between the firing pin and detonator cap, air impinged means connected to the safety means for retaining the same in and removing it from the fuse, an inertia responsive body positioned in said fuse for movement longitudinally thereof, and means on said inertia body effective when the body is in its forward position for retaining the air impinged means in inoperative position. 5

6. In a projectile fuse, the combination comprising a detonator cap and a firing pin mounted for relative movement longitudinally of the fuse, safety means removably mounted in said fuse for preventing contact between the firing pin and detonator cap, air impinged means connected to the safety means for retaining the same in and removing it from the fuse, an inertia responsive body positioned in said fuse for movement longitudinally thereof, means on said inertia body effective when the body is in its forward position for retaining the air impinged means in inoperative position, and means frangible under projection impact for retaining said body in its forward position. 10

7. In a projectile fuse, the combination comprising a detonator cap and a firing pin mounted for relative movement longitudinally of the fuse, safety means removably mounted in said fuse for preventing contact between the firing pin and detonator cap, air impinged means connected to the safety means for retaining the same in and removing it from the fuse, an inertia responsive body positioned in said fuse for movement longitudinally thereof, means on said inertia body effective when the body is in its forward position for retaining the air impinged means in inoperative position, and locking means on said body for directly engaging the safety means when the body is in its forward position to retain the safety means in effective 25 position. 30

8. In a projectile fuse, the combination comprising a detonator cap and a firing pin mounted for relative movement longitudinally of the fuse, safety means removably mounted in said fuse for preventing contact between the firing pin and detonator cap, air impinged means connected to the safety means for retaining the same in and removing it from the fuse, an inertia responsive body positioned in said fuse for movement longitudinally thereof, means on said inertia body effective when the body is in its forward position for retaining the air impinged means in inoperative position, locking means on said body for directly engaging the safety means when the body is in its forward position to retain the safety means in effective 40 position, and means frangible under projection impact for retaining said body in its forward position. 45

9. In a projectile fuse, the combination comprising a detonator cap and a firing pin mounted for relative movement longitudinally of the fuse, safety means removably mounted in said fuse for preventing contact between the firing pin and detonator cap, air impinged means connected to the safety means for retaining the same in and removing it from the fuse, an inertia responsive body positioned in said fuse for movement longitudinally thereof, means on said inertia body effective when the body is in its forward position for retaining the air impinged means in inoperative position, and means frangible under projection impact for retaining said body in its forward position. 50

10. In a projectile fuse, the combination comprising a detonator cap and a firing pin mounted for relative movement longitudinally of the fuse, safety means removably mounted in said fuse for preventing contact between the firing pin and detonator cap, air impinged means connected to the safety means for retaining the same in and removing it from the fuse, an inertia responsive body positioned in said fuse for movement longitudinally thereof, means on said inertia body effective when the body is in its forward position for retaining the air impinged means in inoperative position, and means operative upon release of the air impinged means for moving it into a position to be impinged by the air through which the projectile passes. 60 65 70 75

10. In a projectile fuse, the combination comprising a detonator cap and a firing pin mounted for relative movement longitudinally of the fuse, safety means removably mounted in said fuse for preventing contact between the firing pin and detonator cap, air impinged means connected to the safety means for retaining the same in and removing it from the fuse, an inertia responsive body positioned in said fuse for movement longitudinally thereof, means on said inertia body effective when the body is in its forward position for retaining the air impinged means in inoperative position, means frangible under projection impact for retaining said body in its forward position, and means operative upon release of the air impinged means for moving it into a position to be impinged by the air through which the projectile passes.

11. In a projectile fuse, the combination comprising a casing, a detonator cap and a firing pin mounted for relative movement longitudinally of the fuse, a safety slide removably mounted in the casing for preventing contact between the firing pin and detonator cap, a cowl positioned on the exterior of said casing, means connecting one side of said cowl to said slide, detachable connecting means associated with the other side of the cowl, a heavy annular mass mounted in said casing and embracing said detonator cap, and a projection on said annular mass adapted to cooperate with said detachable connecting means to secure the same on the casing when the mass is in its normal position and adapted to release the same when the mass is retracted upon projection impact.

12. In a projectile fuse, the combination comprising a casing, a detonator cap and a firing pin

mounted for relative movement longitudinally of the fuse, a safety slide removably mounted in the casing for preventing contact between the firing pin and detonator cap, a cowl positioned on the exterior of said casing, means connecting one side of said cowl to said slide, detachable connecting means associated with the other side of the cowl, a heavy annular mass mounted in said casing and embracing said detonator cap, a projection on said annular mass adapted to cooperate with said detachable connecting means to secure the same on the casing when the mass is in its normal position and adapted to release the same when the mass is retracted upon projection impact, and frangible means adapted to break under projection impact for retaining said annular mass in a position to secure the cowl to the casing.

13. In a projectile fuse, the combination comprising a casing, a detonator cap and a firing pin mounted for relative movement longitudinally of the fuse, a safety slide removably mounted in the casing for preventing contact between the firing pin and detonator cap, a cowl positioned on the exterior of said casing, means connecting one side of said cowl to said slide, a movable wing attached to the other side of the cowl, detachable connecting means associated with said wing, a heavy annular mass mounted in said casing and embracing said detonator cap, and a projection on said annular mass adapted to cooperate with said detachable connecting means to secure the same on the casing when the mass is in its normal position and adapted to release the same when the mass is retracted upon projection impact.

LUIGI SAVANI.
